INVENTOR,
L. V. Poppelman,
By Howard A. Smith
ATTORNEY.

UNITED STATES PATENT OFFICE.

FRANK H. POEPPELMEIER, OF DAYTON, OHIO, ASSIGNOR OF ONE-FOURTH TO LAWRENCE A. POEPPELMEIER, ONE-FOURTH TO VINCENT E. POEPPELMEIER, AND ONE-FOURTH TO JOHN L. WEIGAND, ALL OF DAYTON, OHIO.

TYPE-COMPOSING MACHINE.

Application filed April 4, 1927. Serial No. 180,698.

It is the principal object of my invention to provide for a composing machine of the type disclosed in my United States Letters Patent No. 1,607,170, granted November 16th, 1926, a type receiving drum or flat chase which will be so indexed as to be properly located at all times, irrespective of any errors in it. This is accomplished by my improved means for indexing the drum or flat chase at its type receiving end.

It is another object of my invention to provide improved means for locking the type receiving drum on its eccentric shaft.

Other important and incidental objects will be brought out in the following specification and particularly set forth in the subjoined claims.

In the accompanying drawings illustrating my invention, Figure 1 is a rear view of the composing machine, partly in section, showing the chase indexing and locking mechanism. Figure 2 is a sectional side view of the same. Figure 3 is an enlarged sectional view taken through the indexing and locking mechanism. Figure 4 is a cross sectional view taken on the line 4-4 of Figure 1. And Figure 5 is a perspective view of the trip pawl and associated parts.

Referring to the accompanying drawings for a detailed description of my invention, the numeral 1 designates a chase support upon which there is mounted a casting 2 that carries an ejector housing 3. Mounted in the latter is a horizontal shaft 4 that projects at one end beyond the housing to receive a sprocket 5.

One side face of the ejector housing 3 is formed with a deep recess 6 for a crank disc 7 fast on the outer end of the shaft 4. For the purpose of rotating the crank disc 7, the sprocket 5 is connected by a sprocket chain 8 with a sprocket 9 secured to a clutch member 10 which is free to rotate about a chase index shaft 11. (See Figure 1.)

The clutch member 10 is rotated by a sleeve 12 through friction discs not shown within it. The sleeve 12 is in turn rotated by an electric motor 13 through a geared

connection with its armature shaft 14 with-
in a gear box 15. (See Figure 1.)

Formed on the crank disc 7 is a crank pin 16 that is fitted into a hole in the rear end of an ejector arm 17 of the type ejecting mechanism shown and described in my said United States Letters Patent No. 1,607,170, although any other suitable type ejection mechanism may be employed if desired. By the ejector arm 17 the selected type is ejected upon a chase such as the drum 18. (See Figures 1 and 2.)

The drum 18 is applied to an eccentric shaft 19 journaled at its rear end in a bronze bearing 20 fitted in a hole in the casting 2. The front end of this shaft 19 is journaled in a bearing 21 fitted in a hole in the sup-
port 1.

The eccentric portion of the shaft 19 is its middle part. At the front end of the latter there is freely mounted upon the shaft 19 a drum disc 22 into the center of which 70 a bushing 23 is pressed. This bushing, which is permitted a free rotation upon the shaft 19, has a shoulder 24 which abuts the shoulder formed by the eccentric portion of said shaft. Secured to the shaft 19 in front 75 of the drum disc 22 is a collar 25 to hold the latter in its proper floating position upon the shaft.

A similar drum disc 26, having in its central portion a shouldered bushing 27, like 80 the bushing 23, is freely mounted on the shaft 19 at the other end of its eccentric portion. This drum 26 is floatingly held upon the shaft 19 by a collar 28 secured to the latter.

The lower semi-circular portions of both drum discs 22 and 26 are filled with lead or other weighty substance to counter-balance the weight of the chase drum 18 which is easily applied to the eccentric portion of 90 the shaft 19 by the following means.

Upon the top portions of the disc drums 22 and 26, which are flattened to receive a flat chase when one is used, the drum 18 is mounted. Upon the inner surface of the 95 drum 18 are two pairs of ears 29.

Each pair of ears 29, 29 supports a hinge pin 30 for the upper end of a spring clamp 31. These clamps 31, 31 are formed in **U** shape at their bottom portions to fit tightly around the eccentric part of the shaft 19, from which they are readily removed by turning the eccentric shaft 180° by means of a handle 32 applied to its front end. Thus the drum 18 may be easily secured to the shaft 19, and removed therefrom without the necessity of prying it out with a screw driver or other instrument. (See Figure 2.)

For the purpose of properly locating the drum 18 to receive the selected type from the ejector, the following means are employed. Pivotaly mounted on a stud 33 secured to the chase support 1 is a vertically disposed index pawl operating lever 34 which carries on its upper end a fulcrum pin 35. Pivotaly secured at its rear end to this pin 35 is an index pawl 36 formed at its front end with a downwardly projecting nose 37 adapted to engage at their type receiving ends, the conventional **T** slots 38 formed in the periphery of the drum. (See Figures 1 and 2.)

Adapted to slide upon the shaft 11 for the purpose to be hereinafter described, is a drum cam 39 formed with two cam grooves 40 and 41. Carried by the lower end of the lever 34 is a roller 42 which is received by the groove 40 in said cam. (See Figure 1.)

The drum cam 39 is rotated from the shaft 11 by a collar 43 pinned to the latter and formed with two axial pins 44, 44 adapted to enter holes in the adjacent face of said cam. (See Figure 1.)

For the purpose of rotating the shaft 11 at the time it is desired to index the drum 18, the following means are provided. Beyond an oil-less bearing 45 in the casting 2, for the shaft 11, there is pinned to the latter a clutch spool 46 and an outer clutch ring 47. (See Figure 1.)

Formed in the continuously rotating clutch member 10 is an axial hole 48 into which is driven a stud 49 formed with a shoulder 50. (See Figure 1.) Longitudinally slidale from a groove in the spool 46, to a position in front of the shoulder 50 of the stud 49, is a clutch trip 51 formed with a slot adapted to receive the lower end of a trip pawl 52. When this trip pawl is raised above the slot by means soon to be described, the clutch trip 51 will be forced in front of the shouldered stud 49 by a compression spring 53 located in a hole in the outer clutch ring 47. (See Figure 1.)

When the clutch trip 51 is thus in a position in front of the shoulder 50 of the stud 49, the clutch member 10 will rotate the shaft 11 until the trip 51 is restored to its normal position in the slot of the clutch

spool 46 by the spring means now to be described.

The pawl 52, which engages in the slot of the clutch trip 51, is fulcrumed on a pin 54 secured to the casting 2. (See Figure 2.) To the rear end of said pawl is connected one end of a tension spring 55 whose other end is secured by a pin 56 to said casting. This spring is so tensioned as to hold the nose of the pawl 52 in the slot in the clutch trip 51 until it is withdrawn by the solenoid means soon to be described.

As shown in Figure 5, the pawl 52 is formed at its front end with an overhanging shoulder 57 and a downwardly projecting nose 58 which is received by the slot in the clutch trip 51. Just above its nose 58 the pawl 52 is formed with a beveled cam surface 59 which is milled on it. After the clutch trip 51 has made one revolution with the rotating clutch member 10 to which it is connected by its engagement with the stud 49, the thin cam portion 59 of the pawl 52 will wedge into the slot in the clutch trip 51 to slide it back and away from the stud 49 against the compression of the spring 53, until said clutch trip has entirely cleared the stud, whereupon the clutch member 10 will be free to rotate without turning the shaft 11.

For the purpose of lifting the nose 58 of the pawl 52 above the slot in the clutch trip 51 to index the drum 18 one space or more, I provide a conventional electrical solenoid 60 whose plunger 61 is adapted to engage the shoulder 57 on the pawl. Therefore, when the solenoid 60 is energized through means connected with a typewriter keyboard (not shown), the plunger will be raised into engagement with the shoulder 57 on the pawl 52 to lift its nose 58 above the slot in the trip 51, whereupon the latter will be forced in front of the stud 49 by the spring 53, to connect the clutch member 10 with the shaft 11. The latter will then turn the cam drum 39 to actuate the lever 34 which will cause the index pawl 36 to turn the drum one space for every revolution of the shaft 11. Since the engagement of the projection 37 on said pawl 36 is at the type receiving end of the drum 18, the latter will be properly indexed at all times to receive the ejected type, irrespective of any irregularities in the machining of the drum, or flat chase plate where one is employed.

For the purpose of lifting the projection 37 of the indexing pawl 36 out of the **T** slot 38 which it has engaged to clear the latter when said pawl is moved rearwardly by the lever 34, the following means are provided. Secured to the pin 35 is the front end of a spring lever 62 which at its rear end carries a pin 63 that is fitted in a slot 64 in the upper end of a link 65. The latter is pivotally

connected at its lower end to one end of a bell crank 66 which is fulcrumed on a stud 67 driven into the support 1. On the other end of the bell crank 66 is a roller 68 which 5 travels in a groove 69 in a drum cam 70 attached to the shaft 11 beyond a bearing 71 for the latter secured to the support 1. The drum cam 70 is so timed that it will actuate the bell crank 66 to lift the projection 10 37 on the pawl 36 out of a T slot 38 just prior to the rearward movement of said pawl. By means of a torsion spring 72 surrounding the pin 35, pressure is exerted by one end of said spring upon the pawl 36 to 15 force its projection 37 into the next T slot 38 before the forward movement of the lever 34. (See Figure 4.)

For the purpose of locating the drum 18 in its proper relation to the type ejector 20 and for locking the drum in its indexed position, I have provided a locating pawl 72 having a projection 73 adapted to engage the T slot 38 near the type receiving end of the next slot. This locating pawl 72 is 25 fulcrumed on a shaft 74 journaled in a casting 75 secured to the support 1. (See Figures 1 and 5.)

Also secured to the shaft 74 is a spring lever 76 on the upper portion of which there 30 is a projection 77 to which a flat spring 78 is attached. At its lower curved end the spring 78 is adapted to engage a projection 79 on a locating-pawl operating-lever 80 which is loosely mounted at its upper end 35 on the shaft 74. Formed on the lever 80 opposite the projection 79 is a similar projection 81 adapted to be engaged by the lower end of the spring lever 76. (See Figure 1.)

40 The lower end of the lever 80 carries a roller 82 which travels in the groove 41 in the drum cam 39. The groove 41 is so timed that it will actuate the lever 80 and spring lever 76 to engage the projection 73 on the pawl 72 in a T slot 38 immediately after the drum has been indexed by the pawl 36, to hold the drum in proper relation to the type ejector.

When the drum 18 is to be indexed by 50 the pawl 36, the locating pawl 72 is lifted out of its T slot 38 by the drum cam 39 and connected levers 80 and 76.

The speed of the motor-driven clutch member 10 may be regulated through the 55 following brake mechanism. Referring to Figures 1 and 2, the numeral 83 designates a brake band 84 which surrounds the clutch member 10 and which is anchored to a stud 84 secured to the chase support 1. This 60 band may be tightened or released to retard or quicken the speed of the clutch member 10, by means of a screw 85 which passes through the free ends of the band. On one end of this screw is a nut 86 and surrounding its other end is a spring 87.

In order to facilitate the removal of the drum 18, or a flat chase if employed, the pawls 36 and 72 may be lifted above the chase by moving the drum cam 39 along the shaft 11 toward the cam driver 43. For the 70 purpose of shifting the drum cam 39 along the shaft, said cam is formed at its rear end with a cam groove 88 that receives a roller 89 carried by a crank 90 on a shaft 91 which may be rotated by any suitable manual 75 means, such as a handle 92.

Having described my invention, I claim:

1. In a type composing machine, a type 80 ejector, a movable slotted chase for receiving type from said ejector, and means engageable with the slotted portion of the type receiving end of said chase for indexing the latter.

2. In a type composing machine, a type 85 ejector, a movable slotted chase for receiving type from said ejector, means engageable with the slotted portion of the type receiving end of said chase for indexing the latter, and means also engageable with said chase near its type-receiving end for locking said 90 chase in its indexed position.

3. In a type composing machine, a type 95 ejector, a slotted chase for receiving type from said ejector, and a member engageable in a slot near the type receiving end of said chase for indexing the latter.

4. In a type composing machine, a type 100 ejector, a slotted chase for receiving type from said ejector, a pawl for engagement with said chase near its type receiving end, and means for engaging said pawl in a selected slot in the chase and for imparting thereafter to the pawl a forward movement to index the chase.

5. In a type composing machine, a type 105 ejector, a slotted chase for receiving type from said ejector, an indexing pawl for engagement in a slot in said chase near its type receiving end, a locating pawl for engagement in a slot in said chase behind the 110 first slot and near its type-receiving end to lock said chase in its indexed position, and drum cam means for imparting a longitudinal movement to the indexing pawl and a vertical movement to the locating pawl for 115 the purpose specified.

6. In a type composing machine, a type 120 ejector, a movable type chase adapted to receive type from said ejector, a pawl adapted to engage said chase near its type receiving end to index it, an index lever to one end of which said pawl is secured, a drum cam adapted to actuate the other end of said lever, a shaft to which said drum is secured, power-driven means, a clutch between said power-driven means and said shaft, and a clutch trip for engaging and releasing said clutch to index the chase a desired degree.

7. In a type composing machine, a type 125 ejector, a movable slotted chase adapted to 130

receive type from the ejector, an indexing pawl having a projection for engagement in the slots of said chase near its type receiving end, a lever secured at one end to 5 said pawl to impart to it a longitudinal movement, a locating pawl having a projection for engagement in the slot next to and near the type receiving end of the slot engaged by the index pawl, lever means for imparting a vertical movement to said locating pawl to move the projection on the latter into and out of the slots in the chase beneath it, and a drum cam for sequentially operating the indexing pawl and the locating pawl 10 lever means.

8. In a type composing machine, a type 15 ejector, a movable slotted chase adapted to receive type from the ejector, an indexing pawl having a projection for engagement in the slots of said chase near its type receiving end, a lever secured at one end to 20 said pawl to impart to it a longitudinal movement, a locating pawl having a projection for engagement in the slot next to and near the type receiving end of the slot engaged by the index pawl, lever means for imparting a vertical movement to said locating pawl to move the projection on the latter into and out of the slots in the chase 25 beneath it, a shaft, means for rotating said shaft, a drum cam slidable on said shaft for rotation by it to sequentially operate the indexing pawl and the locating pawl lever means, and means for shifting said 30 cam on the shaft in a direction to raise both pawls above the chase to permit its removal.

9. A shaft, means for rotating said shaft, a drum cam slidable on said shaft for rotation by it to sequentially operate the indexing pawl and the locating pawl lever means, said cam formed with a shifting groove, and crank means engageable in said groove for shifting the drum cam in a direction to raise both pawls above the chase to permit its removal.

10. In a type composing machine, a type 40 ejector, a movable slotted chase adapted to receive type from the ejector, a locating pawl for vertical engagement in a slot in said chase near its type receiving end, a shaft to which said pawl is secured, a spring lever also secured to said shaft, a lever loosely mounted on said shaft and formed 45 with two oppositely disposed projections, a flat spring secured to the spring lever for engagement with one projection, said spring lever adapted to be engaged by the other projection, and a drum cam for actuating the second lever to engage the spring lever and through it to vertically move the pawl into and out of engagement with the slots in said chase.

11. In a type composing machine, a type

ejector, a movable slotted chase adapted to 65 receive type from the ejector, a lever, a drum cam for reciprocating said lever, a fulcrum pin carried by said lever, an indexing pawl secured to said pin, and having a projection adapted to engage in the slots 70 in said chase, a rearwardly projecting arm secured to said fulcrum pin, a bell crank lever actuated by the drum cam, and linkage connected between said arm and the bell crank lever for the purpose specified. 75

12. In a type composing machine, a type 80 ejector, a movable chase adapted to receive type from the ejector, means engageable with said chase near its type receiving end to index the latter, a shaft, cam means on said shaft for actuating the indexing means, a power-driven clutch member surrounding said shaft, a stud projecting from the face of said member, a sleeve formed with an axial groove secured to the shaft, a clutch trip free to move from the groove in said sleeve into a position in front of said stud whereby the shaft may be rotated by the power-driven clutch member, a spring for forcing said trip into a position in front of said stud, said trip formed with a groove, a pawl fitting the second groove, and means for raising said pawl above the second groove, whereby the clutch trip will be forced by its spring into a position in front of the stud for the purpose specified. 85

13. In a type composing machine, a type 90 ejector, a movable chase adapted to receive type from the ejector, means engageable with said chase near its type receiving end to index the latter, a shaft, cam means on said shaft for actuating the indexing means, a power-driven clutch member surrounding said shaft, a stud projecting from the face of said member, a sleeve formed with an axial groove secured to the shaft, a clutch trip free to move from the groove in said sleeve into a position in front of said stud whereby the shaft may be rotated by the power-driven clutch member, a spring for forcing, said trip in front of said stud, said trip formed with a groove, a pawl having a nose portion engageable in the groove in the clutch trip, a shoulder on said pawl above its nose portion, a solenoid, and a plunger in the latter for engagement with said shoulder to raise the nose portion of the pawl above the clutch trip for the purpose specified. 95

14. A chase holding means comprising a shaft, a pair of supporting discs loosely mounted on said shaft and having weighted portions, a chase for support by said discs, and spring clamps secured to said chase for engagement with said shaft between the discs to hold the chase firmly thereon. 100

15. A chase holding means comprising a shaft, formed with an eccentric portion,

a pair of drum discs loosely mounted on said shaft, one on each side of its eccentric part and having weighted portions, a drum adapted to receive type from the 5 ejector, mounted on the non-weighted parts of said discs, arms hingedly secured to the interior part of said drum, and spring

clamps on the free ends of said arms for engagement with the eccentric part of said shaft to firmly secure the drum to said discs. ¹⁰

In testimony whereof I have hereunto set my hand this 2nd day of April, 1927.

FRANK H. POEPPELMEIER.
